VACUUM CABINET FOR MOPS

Paul Bischof, New York, N. Y.

Application June 16, 1938, Serial No. 214,157

4 Claims. (Cl. 15—15)

The main object of this invention is the provision of a vacuum cabinet in which mops are adapted to be shaken, the cabinet having a motor therein which creates a suction to absorb the loosened dust, the motor being reversible through an arc of 180 degrees so that the same may serve as a blower or fan.

The above and other objects will become apparent in the description below in which characters of reference refer to like-named parts in the accompanying drawing.

Referring briefly to the drawing, Figure 1 is a perspective view of the cabinet.

Figure 2 is a cross-sectional view taken on the line 2—2 of Figure 1.

Figure 3 is a cross-sectional view taken on the line 3—3 of Figure 2.

Referring in detail to the drawing, the numeral 10 represents a cabinet which may, however, be of any other suitable shape or form than that shown, the latter serving for the purposes of illustration only. Near the top of the cabinet 10 a horizontal screen 12 rests upon a peripheral ledge 14, defining a compartment 13 between the screen 12 and the roof of the cabinet. In the front wall 14, an opening is formed into the compartment 13, and a door 15 is mounted therein. Similar openings 16 and 17 are formed in the side walls of the cabinet on the same level as the opening 15. The openings 16 and 17 are covered with a porous or net-like cloth which will permit free access of air or wind therethrough, and likewise the door 15 has opening within its frame which is likewise covered.

At a distance below the screen 12 an electric motor 18 is supported on a shelf 19, the shaft 20 of the motor extending for a distance beyond the motor frame. A housing 21 is supported in the opposite wall of the cabinet and has a horizontal bore in axial alignment with the motor shaft 20, in which a second shaft 22 is rotatably mounted. By means of a set screw 23 a frame 24 is locked on the end of the shaft 22, the sleeve 24a also being in the same axial alignment. At opposite sides of the frame 24, and also in axial alignment with the motor shaft 20, are respectively an opening through which the shaft 20 passes into the frame and in which the motor shaft is rotatable, and a socket 25 in which the end of the motor shaft is rotatably supported. Within the frame 24 a bevel gear 26 is rigid on the motor shaft 20, and this bevel gear is in mesh with a horizontal bevel gear 27 rigid on the lower end of a fan shaft 28 which projects vertically upward through an opening in the top of the frame 24. A fan or

blower 29 is rigid on the upper end of the shaft 28, and lies normally, when the device is ready for use to suck down the dust shaken from a mop, in horizontal position on a level just below the screen 12.

The outer extremity 30 of the shaft 22 is reduced and projects through the front wall 14, and has locked thereon a lever or handle 31. A disc or plate 32, which is integral with the housing 21, lies flush against the outside of the wall 14 and is provided with a pair of peripheral recesses 33 and 34, one vertically above the other. On the extremity of the lever 31 a sleeve 35 is formed in which a pin 36 is slidably mounted, the pin being normally urged through the sleeve against the disc 32 by a spring, not shown, so as to urge the wall end of the pin into one of the recesses 33 or 34 when the handle is rotated into such position that the sleeve 35 will lie adjacent one of the said recesses.

In the lower part of the cabinet 10 the front wall 14 is provided with a horizontally hinged door 37 which is adapted to open inward, as shown, and when in fully opened position is adapted to have its upper edge rest against the wall 38 of the cabinet. Near the bottom of the rear wall 38 an opening 39 is formed and provided with a peripheral flange 40. A bag 41, of the type usually used with vacuum cleaners, whose opening is at its lower end, is adapted to be secured over the flange 40 by its open end and to have its other end suspended from a hook 42 on the rear wall 38.

When it is desired to shake the dust out of a mop, the door 15 is opened and the mop is inserted through the opening thereof, with the motor running and the fan 29 in the position shown in full lines in Figure 2. The mop is simply shaken in the same manner as it would be shaken out of doors, and the dust freed therefrom is sucked down by the fan 29 through the screen 12 and into the bag 41. When it is desired to use the device as a fan for cooling purposes, the handle 31 is rotated through 180 degrees, after first pulling the pin 36 out of the recesses 34, and in its new position the pin 36 is permitted to enter the recess 35. Thus, the frame 24 has likewise been rotated through the same arc, and the fan 29 now takes the position shown in broken lines in Figure 2 and acts as a blower, forcing air up from the bottom of the cabinet through the screen 12 and out of the porous openings 16 and 17 and of the door 15. When using the device as a fan the door 37 is pushed open into the position shown in broken lines in Figure 2, so that

it acts as a baffle to guide the incoming air outward toward the fan. When the cabinet is not being used as a suction apparatus, the bag 41 may be detached and kept in the bottom of the 5 cabinet or in any other suitable place, so that the cabinet will have an attractive and ornamental appearance and be of use as an article of furniture in the home.

Obviously, modifications in form and structure 10 may be made without departing from the spirit and scope of the invention.

I claim:

1. A device of the class described comprising a cabinet having an opening in its front wall near the top, a horizontal screen mounted within the cabinet near the base of said opening, a motor mounted below said screen and having its shaft extending horizontally therefrom, a housing mounted on the opposite wall of the cabinet and 20 having a bore therethrough in axial alignment with said motor shaft, a second shaft rotatably mounted in said bore, one end of said second shaft extending toward said motor shaft and the other end extending through said housing and 25 said opposite wall to the outside of the latter, a frame having an opening through one side thereof and a socket in the other side thereof in axial alignment with said frame opening, said motor shaft passing through said frame opening and 30 having its end registering in said socket, a sleeve on said frame also in said axial alignment, said one end of said second shaft being locked in said sleeve, a fan shaft extending through said frame at right angles to said motor shaft, said fan shaft 35 having a fan on its outer end and having a bevel gear on its end within said frame, a bevel gear on said motor shaft within said frame in mesh with said first-named bevel gear, a handle on the said end of said second shaft which extends 40 through said opposite wall, said frame and said fan shaft and fan being rotatable about said motor shaft as an axis by rotation of said handle.

2. A device of the class described comprising a cabinet having an opening in its front wall near the top, a horizontal screen mounted within the cabinet near the base of said opening, a motor mounted below said screen and having its shaft extending horizontally therefrom, a housing 50 mounted on the opposite wall of the cabinet and having a bore therethrough in axial alignment with said motor shaft, a second shaft rotatably mounted in said bore, one end of said second shaft extending toward said motor shaft and the other 55 end extending through said housing and said opposite wall to the outside of the latter, a frame having an opening through one side thereof and a socket in the other side thereof in axial alignment with said frame opening, said motor shaft 60 passing through said frame opening and having its end registering in said socket, a sleeve on said frame also in said axial alignment, said one end

of said second shaft being locked in said sleeve, a fan shaft extending through said frame at right angles to said motor shaft said fan shaft having a fan on its outer end and having a bevel gear on its end within said frame, a bevel gear on 5 said motor shaft within said frame in mesh with said first-named bevel gear, a handle on the said end of said second shaft which extends through said opposite wall, said frame and said fan shaft and fan being rotatable about said motor shaft 10 as an axis by rotation of said handle, and means for releasably locking said handle selectively in diametrically opposed positions one vertically above the other, said fan when in its upper position functioning as a suction fan and in said lower 15 position as a blower fan.

3. A device of the class described comprising a cabinet having an opening in its front wall near the top, a horizontal screen mounted within the cabinet near the base of said opening, a motor 20 mounted below said screen and having its shaft extending horizontally therefrom, a vertical fan shaft geared to said motor shaft and having a fan rigid on its upper end lying normally just below said screen, said fan being adapted to function as a suction fan to suck air down through said screen in one position and as a blower fan to force air upward through said screen when in a position at 180 degrees therefrom, said cabinet having a door in said front wall below said motor, 30 said door being horizontally hinged on its bottom and being adapted to swing inward until its upper edge contacts the rear wall of the cabinet, said door in said inwardly swung position serving as a baffle to guide incoming air through said door opening upward toward said fan when the latter functions as a blower fan.

4. A device of the class described comprising a cabinet having an opening in its front wall near the top, a horizontal screen mounted within the 40 cabinet near the base of said opening, a motor mounted below said screen and having its shaft extending horizontally therefrom, a vertical fan shaft geared to said motor shaft and having a fan rigid on its upper end lying normally just 45 below said screen, said fan being adapted to function as a suction fan to suck air down through said screen in one position and as a blower fan to force air upward through said screen when in a position at 180 degrees therefrom, said cabinet having a door in said front wall below said motor, 50 said door being horizontally hinged on its bottom and being adapted to swing inward until its upper edge contacts the rear wall of the cabinet, said door in said inwardly swung position serving as a baffle to guide incoming air through said door opening upward toward said fan when the latter functions as a blower fan, 55 said cabinet having an opening through its rear wall at the bottom thereof adapted to have a 60 dust-collecting bag secured thereto.

PAUL BISCHOF.
